Primary Examiner — Ricky Pham(74) *Attorney, Agent, or Firm* — Senniger Powers LLP**CLAIM**

The ornamental design for a container lid, as shown and described.

DESCRIPTION

FIG. 1 is a perspective of an embodiment of a container lid of my new design;

FIG. 2 is a front elevation of the container lid of FIG. 1;

FIG. 3 is a top view of the container lid;

FIG. 4 is a rear elevation of the container lid;

FIG. 5 is a bottom view of the container lid;

FIG. 6 is a right side elevation of the container lid; and,

FIG. 7 is a left side elevation of the container lid.

The broken lines are included for the purpose of illustrating portions of the container lid that form no part of the claimed design.

1 Claim, 6 Drawing Sheets(56)
